BREAKWATER

Harvey J. Humphrey, Euclid Beach Park, Ohio,
assignor of one-half to Dudley S. Humphrey,
Euclid Beach, Ohio

Application December 7, 1938, Serial No. 244,464

4 Claims. (Cl. 61—4)

My invention relates to breakwaters and has for its general object to provide a practically indestructible and comparatively inexpensive perforate breakwater for breaking the force of water adjacent exposed shore lines of lakes, oceans and other bodies of water.

A further object of the invention is to form a breakwater of a plurality of interchangeable spaced and readily removable units or blocks so that the breakwater can be easily built and as easily removed, or the height thereof readily increased or decreased to meet changing conditions.

Another object of the invention is to provide a breakwater which will effectively break the force of incoming water as it passes therethrough in one direction, and slow down the receding body of water, passing therethrough in the opposite direction, to such an extent that the maximum deposit of sand and gravel will take place between the breakwater and the shore.

A still further object of the invention is to so form a breakwater having interstices therein at regular intervals, that the size of the interstices can be readily varied.

Other objects and advantages of the invention will be apparent as the description is considered with the accompanying drawing, in which:

Figure 1 is a plan view of a breakwater embodying my invention;

Figure 2 is a rear fragmental view of a portion of the improved breakwater showing seven tiers or layers of blocks;

Figure 3 is a vertical sectional view on the line 3—3 of Figure 1;

Figure 4 is a perspective view of a breakwater showing the blocks of each tier as being parallel to each other and extending at the same angle to blocks of the next adjacent tier or course;

Figure 5 is a perspective view, partly broken away, of one of the reinforced concrete blocks; and

Figure 6 is a detail sectional view through one of the pipes showing the method of anchoring the pipes in place.

Referring more particularly to the drawing 1 denotes a breakwater positioned in the water 2, a short distance from the shore line 3 which the breakwater is designed to protect. The embodiment illustrated comprises a plurality of reinforced concrete blocks 4, connected together and anchored in the clay bottom 5, by means of iron pipes 6, which pass loosely through openings 7, formed in opposite ends of the blocks. These blocks are identical one with the other but ob-

viously their weight and dimensions will depend largely upon the conditions under which they are used, that is, the nature of the strains and stresses to which the breakwater will be subjected. While rectangular blocks are preferable, because of the facility with which they can be molded and handled, blocks having rounded corners will function equally as well.

In practice two rows 8 and 9 of pipes 6 are anchored in the clay bottom 5, the pipes of one row being preferably but not necessarily staggered with respect to the pipes of the other row. Various methods of sinking the pipe are available but I have found that water under pressure jetted to the bottom of the pipe interiorly thereof as by means of a nozzle 10 quickly forms an excavation beneath the pipe into which the latter can be readily forced by an appropriate rocking movement, the lower extremity of the pipe being formed with serrations 11, to facilitate this operation. The pipes lean or incline slightly away from the shore line for a purpose presently described.

After the rows of pipe have been suitably anchored the blocks are laid in tiers or courses by placing the blocks in interwoven somewhat loose relation over the pipes. It will also be noticed that individual blocks are connected to a pipe of each row of piping and that each block with the exception of the endmost block of each tier is connected at its ends to two adjacent blocks. The diameter of the holes or openings 7 in opposite ends of the blocks are considerably greater than the diameter of the pipes to provide a loose connection between adjacent blocks and courses and to facilitate assembly. These openings are provided with metal sleeves or linings 12, which reduce wear at these points. The lower net work 13 of reinforcing rods 14, for the concrete blocks 4, are welded together and to the sleeve 12 before the concrete is poured in the molds, not shown, and the upper layer or net work 15 of previously joined reinforcing rods is then placed in the mold after the lower layer of rods is covered and the pouring is then continued and the block permitted to set.

After one or more courses of blocks have been assembled the partially completed breakwater is permitted to rest until the bottommost course has settled through the sand 16 and comes to rest upon the solid clay bottom 5. However the settling process being a very rapid one, these operations can be carried out with practically no interruption or delay. The topmost courses or layers of blocks are preferably tied together by 55

readily removable straps or the like 17. Should any slight pivotal or vibrational or other movement of the blocks be caused by the action of water or ice, the same will be distributed to and 5 absorbed at the respective loose pivotal connections between the blocks and supporting pipes.

The angular relationship between adjacent blocks can be varied to suit conditions encountered at any particular point in the breakwater 10 as indicated in Figure 1. Thus the relative angularity of those blocks at the left of Figure 1 is much greater than those at the right of this figure. However, it will be understood that the angularity may and probably will be uniform 15 throughout the entire length of any particular breakwater, in most instances. If the angle is obtuse or opened up, as illustrated in the left-hand portion of Figure 1, less resistance is offered to the flow of water between the blocks 20 and the build up of deposited sand and gravel back of the breakwater will be less and damage to the shore line will be greater, under most conditions, than would be the case where the angularity is more acute, as the closing of the angle 25 between adjacent blocks results in a reduction in the capacity or size of the interstices 18, and a corresponding increased resistance to the uninterrupted flow of waves therethrough. It is a comparatively simple matter to completely or 30 partially disassemble the parts of the breakwater for the purpose of changing the relative angularity of the blocks or for moving the breakwater away from or toward the shore line as experience dictates. Or having answered its purpose, the 35 breakwater can be economically disassembled and shipped to a distant point or stored for future use.

By inclining the pipes 6, forwardly or away from the shore line, the concrete blocks 4 will 40 slope correspondingly and water surging through the interstices 18, will be directed upwardly and consequently will not have a tendency to dig into the beach or shore line with excavating effect. The most effective slope for a particular 45 location can be quickly determined by varying the inclination of the pipes at different places throughout the length of the breakwater for purposes of observation. Any change in the slope of the blocks which experience indicates as being 50 advisable can be readily made without injury to the blocks or pipes.

Observation over a period of several weeks, of a breakwater constructed in accordance with the present invention and placed some distance from 55 the beach in several feet of water, has proven that the washing away of a considerable length of shore line was not only quickly checked, but that the beach was actually extended several feet, almost to the breakwater, by the deposit of sand and gravel carried through the interstices 60 18 by the waves or water 2 from outside the breakwater and deposited by the subdued or receding body of water 2' as the latter recedes from the beach toward and outwardly through the 65 breakwater.

Water is excluded from the pipes 6 by filling the latter with cement, with or without reinforcing rods, not shown, but sand will effectively answer this purpose and prevent bursting of the pipes in most climates. Contraction and expansion due to changes in temperature is compensated for by reason of the angular arrangement of the blocks and the loose and more or less pivotal connection between adjacent blocks of each tier of blocks.

When the prevailing wind is in a direction oblique to the shore line littoral currents set up between the shore line and the breakwater will have a tendency to offset the beneficial effects of the breakwater. To overcome this, I provide 15 at one or both ends of the breakwater, a jetty 19 constructed in the same manner as the breakwater 1.

Having thus described my invention, what I 20 claim is:

1. A breakwater comprising tiers of superimposed blocks, certain of the blocks of a tier extending in substantially the same parallel direction, and certain of the blocks of the next adjacent tier extending substantially parallel to 25 each other but at an angle to said first mentioned certain blocks, and means for loosely connecting the blocks of one tier with each other and with the blocks of the next adjacent tier.

2. A breakwater comprising substantially horizontally disposed layers of blocks arranged substantially parallel to the shore line, the blocks of one layer being angularly arranged with respect to each other and to the blocks of the next adjacent layer to form openings, and common 35 means for connecting said blocks together and for anchoring the breakwater in place, and at least certain of said blocks being inclined from a horizontal plane downwardly and rearwardly 40 toward said shore line.

3. A breakwater comprising tiers of superimposed blocks, the blocks of each layer being spaced from the next adjacent blocks of that layer, each block of one layer, except the end blocks thereof, resting at its ends upon the ends 45 of the block of the next adjacent layer therebeneath, the blocks of one tier having end openings adapted to register with corresponding openings in the blocks of the other tiers, and means extending loosely through said openings 50 for connecting the blocks of each pair together for relative pivotal movement with respect to each other and for anchoring the breakwater in place.

4. A breakwater comprising tiers of superimposed blocks, the blocks of each tier being spaced apart from each other and the blocks of one tier being angularly arranged with respect to the blocks of the next adjacent tier to form interstices, all of said blocks being inclined upwardly 60 and rearwardly from the horizontal, and means for readily detachably and pivotally securing said tiers of blocks together and for anchoring the breakwater in place.
